ATTORNEY.

UNITED STATES PATENT OFFICE.

HUGH R. MCALISTER, OF PHILADELPHIA, PENNSYLVANIA.

BRAKE-SHOE.

SPECIFICATION forming part of Letters Patent No. 224,456, dated February 10, 1880.

Application filed July 11, 1879.

To all whom it may concern:

Be it known that I, HUGH R. MCALISTER, of the city and county of Philadelphia, and State of Pennsylvania, have invented a new and useful Improvement in Brake-Shoes, which improvement is fully set forth in the following specification and accompanying drawings, in which—

Figure 1 is a side elevation of the brake-shoe embodying my invention. Fig. 2 is a central vertical section thereof. Fig. 3 is a front view of the stock of the shoe. Fig. 4 is a view of the inner face of the liner.

Similar letters of reference indicate corresponding parts in the several figures.

My invention consists in securing the liner or facing to the stock by means of V-shaped or segmental flanges which are formed on the facing and stock, respectively, and engage one with the other by lateral motion of either part.

The stock has at its upper end two flanges, the centers or crowns of which face inwardly or in opposite directions, and the liner has at its upper end a flange which enters between the two flanges of the stock, and then drops in position so as, with the assistance of the lower flanges, to lock the liner and stock without the employment of bolts, pins, or keys.

It also consists in securing the stock and block by means of a T-headed bolt, as will be hereinafter set forth.

Referring to the drawings, A represents the stock of the shoe, the same having on its front face at top a flange, a, adjacent thereto a flange, b, and at bottom a flange, c, the several flanges extending transversely and formed of V-shaped or segmental pieces.

The segmental or V edges of the flanges b c face each other, and the edge of the bottom flange, c, has its center pointing or facing downward.

B represents the liner or facing of the shoe, and consists of a detachable piece having on its inner face upper and lower V-shaped or segmental flanges d e, which point or face in opposite directions, as shown.

The flange d is adapted to engage with the flanges a b, and the flange e with the flange c, and the contiguous faces of the flanges are dovetailed.

The operation is as follows: In order to ap-

ply the liner to the stock the liner is turned so that the flange e is presented to the flange c, and then partially engaged, and the flange d directed between the flanges a b and forced in to full extent.

It will be seen that the flanges a b d are locked at the top of the liner and stock, and the flanges c e at the bottom thereof, whereby the liner is securely held to the stock and prevented from longitudinal or vertical displacement.

The strength of the locked connection of the liner and stock is further increased by hooks C, which project from the back of the liner at the top and bottom thereof, and are adapted to overhang the top and bottom edges of the stock, thus providing an additional connection for the liner and stock and means for receiving the strain of the liner when the brakes are applied. By properly rotating the liner the several flanges disengage, and thus the liner may be removed.

During the application and removal of the liner the hooks C present no obstacles to either movement, and when the liners are in position and operation, while they are securely held and prevented from lateral displacement, the flanges of the car-wheels serve as further barriers to such displacement, thus insuring the operation and service of the liner.

D represents the block, which is connected to the stock by means of a T-headed bolt, E, the head whereof is passed through a narrow opening, f, in the stock, and when turned at a right angle to said opening rests on the side walls thereof. Consequently, when the nut of the bolt is tightened against the beam F the stock and block are securely connected, the security being increased by the side walls, g, of the block overlapping the back of the stock, and flanges h at the top and bottom of said back embracing middle portion, h', of the block.

When the block and stock require separation for any cause whatsoever, the nut of the bolt E is loosened, and the bolt turned until its head registers with the opening f in the stock, whereby the parts are disconnected. The bolt may now be withdrawn, and its head will pass freely through the opening f.

It will be seen that the stock and block may be connected and disconnected without removal

of the liner, as the position and operation of the bolt E do not interfere with the liner. The improper rotation of the bolt is prevented by its head engaging with or dropping in shoulders or notches *k* on the side walls of the stock.

It will also be seen that the liner and stock are connected without bolts, pins, screws, or similar fastenings.

Having thus described my invention, what I claim as new, and desire to secure by Letters Patent, is—

1. The stock A, having at its upper end two dovetail flanges, *a b*, the centers or crowns whereof face in opposite directions, and at its other end a dovetail flange, *c*, in combination with the liner having dovetail flanges *d e* at opposite ends, the several flanges being V-shaped or segmental, substantially as and for the purpose set forth.

2. The stock A, with flanges *a b c*, in combination with the liner B, with flanges *d e*, and hooks C C, substantially as and for the purpose set forth.

3. The stock A, having a narrow opening, *f*, 25 the T-headed bolt E, and the block D, combined and operating substantially as described, whereby the stock and block may be connected and separated without removal of the shoe-liner, as stated. 30

4. The T-headed bolt and block D, in combination with the stock A, formed with the shoulders or notches *k*, substantially as and for the purpose set forth.

HUGH R. McALISTER.
